UNITED STATES PATENT OFFICE.

GEORGE A. SAAL, OF YOUNGSTOWN, OHIO.

CLOSET-TANK FLUSH-LEVER.

1,250,026.

Specification of Letters Patent. Patented Dec. 11, 1917.

Application filed May 31, 1917. Serial No. 172,022.

To all whom it may concern:

Be it known that I, GEORGE A. SAAL, a citizen of the United States, residing at Youngstown, in the county of Mahoning and State of Ohio, have invented certain new and useful Improvements in Closet-Tank Flush-Levers; and I do hereby declare the following to be a full, clear, and exact description of the invention, such as will enable others skilled in the art to which it appertains to make and use the same.

This invention relates to improvements in a closet tank flush lever and more particularly to means for unseating the flush valve, and has for one of its objects the provision of a device of this character, which will rock the lever upon its pivot to unseat the valve and which will permit the valve to return to a seated position without the binding of the parts that is frequent in devices now in use.

Another object of this invention is to provide means, which will permit the operating means to be rotated in a complete revolution when desired, and which is so constructed that a one-quarter turn will be sufficient to unseat the valve.

A further object of this invention is the provision of a trammel wheel operatively connected to the lever whereby upon rotating the operating means, the trammel wheel will rock the lever upon its pivot to unseat the valve.

A still further object of this invention is the provision of a closet tank flush lever of the above stated character, which shall be simple, durable and efficient, and which may be manufactured and sold at a comparatively low cost.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawing, in which:

50 Figure 1 is a vertical sectional view of a closet tank flush lever constructed in accordance with my invention,

Fig. 2 is a fragmentary longitudinal sectional view of the same,

55 Fig. 3 is a sectional view taken on the line 3—3 of Fig. 2,

Fig. 4 is a plan view of the handle, Fig. 5 is a plan view of the trammel wheel. Referring in detail to the drawing, the numeral 1 indicates a flush tank having secured to its bottom wall in the usual manner, the outlet pipe 2. The outlet pipe 2 has formed upon its upper end within the flush tank 1, a valve seat 3, for receiving a float valve 4 of the ordinary construction having the stem 5. The stem 5 being slidably mounted within the guide 6 carried by a guide rod 7 secured vertically within the flush tank 1. The aforescribed construction relates to a well known construction of flush tank and to which my invention is applied.

The flush tank 1 is provided with an opening in its front wall to receive a cylindrical supporting member 8, which has its outer end screwthreaded to receive a stuffing box 9.

Formed upon the inner end of the cylindrical supporting member 8 is a plate 10 to which is pivoted a valve operating lever 11, as illustrated at 12. The free end of the lever 11 has pivotally secured thereto, a link 13, which is in turn pivoted to the stem 5 of the valve 4 as shown at 14. A substantially U-shaped hanger 15 is formed upon the plate 10 and slidably receives the operating lever 11 as shown in Fig. 1.

A rod 16 is inserted through an aperture in the plate 10 and the supporting member 8 and has secured to its outermost end, a handle 17 by fastener 18. A trammel wheel 19 is formed upon the inner end of the rod 16 and supports a roller 20, which is journaled to an arm 21. The arm 21 has its lower end bifurcated and pivoted to the lever 11 as shown at 22, whereby upon rotating the rod 16 by the handle 17, the trammel wheel 19 will rock the lever 11 upon its pivot 12 and unseat the valve 4, permitting the water within the flush tank 1 to pass outwardly through the outlet pipe 2. It will therefore be seen that a device has been provided, for rocking the lever 11, which may be turned a complete revolution when desired and also will unseat the valve 4 by turning the rod one-quarter of a turn.

It will also be noted that a device constructed in accordance with the above described construction will operate under all circumstances and obviate binding of the various parts, which are frequent within devices now upon the market.

2

While I have shown and described the preferred embodiment of my invention, it will be understood that minor changes in construction, combination and arrangement of parts may be made without departing from the spirit and scope of the invention as claimed.

Having thus described my invention, what I claim is:

10 1. A device of the character set forth comprising a plate, a lever pivoted to said plate, means for connecting said lever to a valve, and a trammel wheel operatively connected with the lever for rocking said lever upon its pivot to unseat the valve.

15 2. A device of the character set forth comprising a plate, a lever pivoted to said plate, means for connecting said lever to a valve, an operating rod carried by said plate, and a trammel wheel carried by the operating rod and operatively connected with the lever to rock it upon its pivot to unseat the valve.

20 3. A device of the character set forth comprising a cylindrical supporting mem-

ber, a plate carried by said member, a lever pivoted to said plate, means for connecting the lever to a valve, an operating rod journaled in the supporting member, a trammel wheel formed on said operating rod, a roller carried by said trammel wheel, means for connecting the roller to the lever to rock said lever upon its pivot to unseat the valve.

25 4. A device of the character set forth comprising a cylindrical supporting member, a plate carried by said member, a lever pivoted to said plate, means for connecting said lever to a valve, a guide formed on said plate for slidably receiving said lever, an operating rod journaled in the supporting member, a trammel wheel formed upon said operating rod and operatively connected with the lever to rock said lever upon its pivot to unseat the valve.

30 In testimony whereof I affix my signature 45 in presence of two witnesses.

GEORGE A. SAAL.
